UNITED STATES PATENT OFFICE.

HUDSON FERRIS, OF CHICAGO, ILLINOIS, ASSIGNOR OF ONE-FOURTH TO
WESLEY C. GARLOCK, OF SAME PLACE.

BURGLAR-ALARM.

SPECIFICATION forming part of Letters Patent No. 355,260, dated December 28, 1886.

Application filed April 23, 1886. Serial No. 199,930. (No model.)

To all whom it may concern:

Be it known that I, HUDSON FERRIS, a citizen of the United States, residing at Chicago, in the county of Cook and State of Illinois, 5 have invented certain new and useful Improvements in Burglar-Alarms, of which the following is a specification, to-wit:

This invention relates to a burglar-alarm; and it consists in certain peculiarities of the 10 construction and arrangement of the same, substantially as will be hereinafter more fully set forth and claimed.

In order to enable others skilled in the art 15 to which my invention appertains to make and use the same, I will now proceed to describe its construction and operation, referring to the accompanying drawings, in which—

Figure 1 is a perspective view of my device set for use. Fig. 2 is a similar view of the 20 device in operation, and Fig. 3 is a side view with one of the side plates removed.

A represents a wedge-shaped block or frame, in the joint of which is pivoted a screw, a, 25 adapted to be engaged with the floor, door, or window-casing, or other object with which the alarm is to be used. In this case it is represented as screwed to the floor just within a doorway and in readiness for use. Within the block or frame is hinged an arm, B, having a hammer-head, B', and in the frame is secured a strong spring, B², which bears against the arm and holds it when open, and forces it 30 shut with sufficient force when closed. The head B' is on its outer side made rough, as at b, for a purpose presently explained, and it is bored out at b' for the reception of a blank cartridge, one of which is shown in position.

The rear end of the wedge-frame is formed 35 with an anvil extension, C, in which is secured a small pin or projection, c, which acts as a firing-pin when the cartridge-holding arm falls, and just beyond this is secured a match-

holder, D, which is adapted to receive and retain a wax match in such a position that the roughened surface of the hammer in falling 45 will scrape the head of the match and ignite it.

In practice the device is secured near a door or window, and set as in Fig. 1. Any attempt to open the door or window at once throws down the arm B with sufficient force to explode the cartridge and give the alarm, while at the same time the match is ignited and a light given, which exposes the burglar and at once shows the location of the attempted entrance. The door or window can also only be 55 opened a slight distance, and is then caught upon the wedge-frame, as represented in Fig. 2, and the device thus acts not only as an alarm, but as a perfect protection against the opening of the object in connection with which it 60 is used.

The present application is for an improvement upon my patent issued to me October 16, 1883, No. 286,598, and is essentially designed to cover the removable match-holder 65 and the means of retaining the match or taper.

Having thus fully described my invention, what I claim as new, and desire to secure by Letters Patent, is—

The combination, in a burglar-alarm, of the 70 wedge-shaped frame A, provided with the screw a, hinged at its point, and the shank C, having the projection c, the spring-actuated arm B, provided with the head B', having serrations b and recess b', and the removable 75 match-holder D, socketed in the shank C, all arranged and operating substantially as shown and described, and for the purpose set forth.

In testimony whereof I affix my signature in presence of two witnesses.

HUDSON FERRIS.
